United States Patent Office

Des. 186,091
Patented Sept. 8, 1959

186,091

PURSE OR SIMILAR ARTICLE

Frank H. Harris, Sunset Hills, Mo.

Application September 3, 1957, Serial No. 47,588

Term of patent 14 years

(Cl. D87—3)

Fig. 1 is a front perspective view of a purse or similar article embodying my new design,
Fig. 2 is a side elevational view; and
Fig. 3 is a rear elevational view.

I claim:

The ornamental design for a purse or similar article,
substantially as shown.
